UNITED STATES PATENT OFFICE

2,369,148

HINGE

Howard C. Langhorst, Dayton, Ohio

Application August 10, 1943, Serial No. 498,051

4 Claims. (Cl. 16—176)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to releasable hinges and more particularly to point bearing, self-aligning and instant parting hinges.

An object of the invention is to provide a readily releasable hinge of the character employed for emergency doors and which is peculiarly adaptable to use on airplane doors, cock-pit inclosures, bomb bays, wing sections, tail pieces and parts which may require instant release or change.

Another object of the invention is to provide a hinge which is automatically adjustable to maintain uniform bearing relationship between journal points and their bearings and manually adjustable to and from frictional locking relationship.

Still another object of the invention is to provide a hinge to which a door or other swinging member may be universally connected in order that such door or member may automatically align itself during moments or conditions which would otherwise subject the same to twisting, warping and other distortions, and whereby a door or other swinging member may be relieved of binding, torsional and other stresses which may be transmitted to the frame upon which the door or swinging member is mounted.

A still further object of the invention is to provide a hinge whereby a door or other swinging member may be readily released under conditions rendering the same or its mounting frame permanently distorted.

With the foregoing and other objects and aims in view, my invention resides in the combination of parts and in the details of construction herein-after set forth in the following specification and appended claims, certain embodiments thereof having the characteristics of my invention and by which the same may be practiced being illustrated in the accompanying drawing, in which:

Fig. 1 is a cross-sectional view taken through the separated hinge members on a plane substantially parallel with the faces of the leaves;

Fig. 2, a view similar to that of Fig. 1, except that the hinge members are shown journaled;

Fig. 3, a cross-sectional view taken as at line 3—3 of the Fig. 2 assemblage; and

Fig. 4, a view similar to that of Fig. 2, but illustrative of a modified embodiment of the journal members of the hinge.

The improved hinge includes male and female

members 10 and 11 intended to be secured to co-operating hinge leaves 12 and 13 or, in the absence of leaves, to be secured one directly to a door, swinging member or panel and the other to a frame or other member on which the former is to be mounted.

The female member 11 is provided with a pair of opposed bearings 14 and 15 adapted to be cooperatively engaged by journal members 16 and 17 carried by the male member 10 in a manner whereby the journal members may be retracted for insertion into the female members and expanded along a predetermined axis into cooperative, pivotal, rotatable or frictional relationship within the female member.

The female member 11 of the hinge may consist

of an anchored reclining-U-shaped member 18, as shown in Figs. 1, 2 and 3, in which the bearings 14 and 15 consist of well-like recesses symmetrically disposed in the inner opposed surfaces of

10 the member, or as shown in Fig. 4, the female portion of the hinge may consist of a pair of anchored plate-like members 18a and 18b, mounted upon the opposed surfaces of a reclining-U-

20 shaped notch 19 in the edge of a door or frame. The male member 10 of the embodiment illustrated in Figs. 1 through 3 includes a journal box 20 in which the journals 16 and 17 are

25 mounted in contiguous relationship, but movable in opposite directions along a predetermined axis, within a journal box bearing 21, by a manually adjustable wedge 22 which may be forced between

30 adjacent ends of the journals, as by a screw 23 to move the journals 16 and 17 into the bearings

35 14 and 15.

In the embodiment of Figs. 1 through 3, the body portions of the journals are cylindrical and their projected ends are shaped as the frustum of a cone and the bearings 14 and 15 of this em-

40 bodiment are of a reverse shape as an inverted truncated cone in order that the journal points may have a greater degree of adjustment, i. e.,

45 from a position allowing considerable play to a frictionally gripping position.

45 The cylindrical shaped body portions of the journals 16 and 17 of the embodiment illustrated in Figs. 1 through 3 may be keyed against rotation

40 within the bearing 21 of the journal box 20 as by keys 24 and 25 slidable longitudinally in

50 a key slot 26 in the wall of the journal box bearing 21, thus to hold the same against rotation when

55 the journals are wedgingly forced into frictional gripping relationship with the bearings 14 and 15

of the female members for locking the hinge

55 members in fixed angular relationship. Such

locking is frequently desired to hold the flaps or tail members of an airplane model in fixed angular position for wind tunnel testing, for holding the wings of a portable screen in fixed angular relationship to the panel thereof, for holding a door ajar, etc.

In the embodiment illustrated in Fig. 4, the male member includes a pair of ball journals 16 and 17 automatically separable along a predetermined axis by a wedge 22 controlled by a spring 27 as distinguished from the manually operable screw 23 of Fig. 1. In this embodiment the bearings of the plate-like members 18a and 18b, forming the female member of the hinge, are unlike in that but one thereof is provided with a well-like bearing, whereas the other is provided with a planar surface upon which one of the ball bearing journals engages surficially and is free to travel thereon, limited only by such angular positions of the journal box with respect to the surfaces of the plate-like members 18a and 18b as will bring about a binding relationship between the sides of the journal box and the surfaces of the female members 18a and 18b. In other words, the hinge member 13 or door is universally pivotable about journal 16. The degree of tilt is limited, however, by an angular impingement of the journal box with the surfaces of the bearing plates. The respective male and female members are, of course, of such size as will allow angular adjustment, the former within the latter, to a degree insufficient to allow the ball journal 16 to be pivoted from its bearing 14. In this embodiment the spring controlled wedge 22 is provided in a shaft 28 whereby the wedge may be retracted manually against the force of the spring 27 to allow the ball journals to move toward one another in order to retract the male member of the hinge for separation thereof.

The members forming the hinge may be secured to leaves or doors and frames by any suitable means, such, for example, as illustrated in the accompanying drawing.

In operation, screw 23 is retracted as in Fig. 1, or the plunger of the Fig. 4 embodiment withdrawn sufficiently to permit the journals to be passed into the female member of the hinge and the journals thence separated into seating relationship with the bearings by a tightening of screw 23 or release of plunger 28. The freedom with which it is desired to have the hinge members work, of the Fig. 1 embodiment, may be governed by the depth to which screw 23 is driven which may be to a point bringing about a frictional gripping between the journals and bearings for locking purposes.

Having described my invention and illustrated embodiments by which the same may be practiced, what I claim is:

1. Means for securing one member angularly adjustable to another comprising a journal box adapted to be secured to one of said members, a pair of journals carried by said journal box,

and a pair of bearings adapted to be secured to the other of said members in spaced axial alignment, one of said bearings being so formed as to receive one of said journals for universal movement therein, the other of said bearings having a planar surface adapted to be surficially engaged by the other of said journals, whereby said journal box may be rotated coaxially of said journals and pivoted universally about the bearing point of one of said journals.

2. Means for securing one member angularly adjustable to another comprising a journal box adapted to be secured to one of said members, a pair of journals carried by said journal box, a pair of bearings adapted to be secured to the other of said members in spaced axial alignment, one of said bearings being so formed as to receive one of said journals for universal movement therein, the other of said bearings having a planar surface adapted to be surficially engaged by the other of said journals, whereby said journal box may be rotated coaxially of said journals and pivoted universally about the bearing point of one of said journals, and means limiting the universal tilt of said journal box to prevent unintentional disengagement of said journals and bearings.

3. Means for securing one member angularly adjustable to another comprising a journal box adapted to be secured to one of said members, a pair of journals carried by said journal box, a pair of bearings adapted to be secured to the other of said members in spaced axial alignment, automatically operable means associated with said journals for wedgingly holding said journals in cooperative relationship with said bearings, said automatically operable means being manually releasable to free said cooperative relationship, one of said bearings being so formed as to receive one of said journals therein, the other of said bearings having a planar surface adapted to be surficially engaged by the other of said journals, whereby said journal box may be rotated coaxially of said journals and pivoted universally about the bearing point of one of said journals, and means limiting the universal tilt of said journal box to prevent unintentional disengagement of said journals and bearings.

4. Means to secure one member angularly adjustable to another comprising a journal box adapted to be secured to one of said members, a pair of journals carried by said journal box, wedge means associated with said journals to move the journals away from each other along a predetermined axis, a recessed bearing and a planar bearing secured to the other of said members in spaced axial alignment to each other to cooperatively engage said journals, said bearings allowing rotation of said journal box coaxially of said journals and allowing a limited universal pivoting of said journal box about the journal engaging the recessed bearing.

HOWARD C. LANGHORST.
